UNITED STATES PATENT OFFICE.

CHARLES J. FANCHER AND ROBERT A. JOHNSON, OF WINDSOR, VERMONT, ASSIGNEES
TO THE NATIONAL ACME COMPANY, OF CLEVELAND, OHIO, A CORPORATION OF
OHIO.

COLLET-FORMING MACHINE.

Application filed December 9, 1920. Serial No. 429,301.

To all whom it may concern:

Be it known that we, CHARLES J. FANCHER and ROBERT A. JOHNSON, both citizens of the United States, residing at 5 Windsor, in the county of Windsor and State of Vermont, have invented certain new and useful Improvements in Collet-Forming Machines, of which the following is a specification.

10 This invention relates to collet forming machines, and particularly to a machine which is adapted to form and shape in a single operation the gripping fingers on pressed steel feed collets for metal working machines.

15 An important object of this invention is to provide a machine adapted to be employed in connection with the manufacture of feed collets shown and described in our 20 co-pending allowed application for an improvement in feed collets, Serial No. 358,501, filed February 13, 1920, and in our co-pending divisional application thereof for the method of making feed collets, Serial No. 25 417,646, filed October 18, 1920, and which machine is simple in construction and operation, durable and effective in use and economical to manufacture.

20 In the manufacture of feed collets in accordance with the methods described in our 30 above co-pending applications, the blank for the collet which is preferably first stamped or otherwise formed out of pressed sheet steel with projecting finger pieces, is 35 placed in a coiling machine and by the action of suitable instrumentalities the blank is bent, rolled or formed up into a hollow feed collet having projecting gripping fingers. This coiling of the blank into the 40 feed collet is described and claimed in our co-pending application for coiling machine, and forms no part of the present invention.

45 After the operation of coiling the blank into the collet having projecting fingers, it is necessary to provide suitable means for forming the fingers of the feed collet into the desired shape, and it is the object of the present invention to provide a collet forming machine which embodies certain novel 50 instrumentalities and mechanism which will in a single operation form the fingers of the collet into the desired shape.

55 Other objects of this invention will appear as the description proceeds, reference being had to the accompanying drawings

forming a part of this specification, wherein like reference characters indicate similar parts throughout the various figures, and wherein Fig. 1 is a front elevation of the present machine; Fig. 2 is a side elevation 60 thereof; Fig. 3 is a detail front view partly broken away and on a somewhat larger scale disclosing the forming mechanism; Fig. 4 is a sectional side elevation thereof; Fig. 5 is a detail plan view partly in section 65 of the slide mechanism for the forming jaws; Fig. 6 is a perspective view of a forming jaw and related parts; Fig. 7 is a detail view showing the jaws in closed position; Fig. 8 is a perspective view of the ejector 70 mechanism; Fig. 9 is a detail view showing the knock-out cam; Fig. 10 is a perspective view of an unformed collet; and Fig. 11 is a perspective view of a formed collet.

Our invention has to do merely with the 75 forming and shaping of the gripping fingers of a feed collet after the same has been coiled or formed up from a sheet metal blank into a hollow tubular form, and in the present instance the various elements 80 making up the invention are incorporated in a suitable power driven machine.

In the machine shown, the framework comprises a standard or base 2 comprising suitable legs 3. The base or bed 2 is 85 provided with upwardly extending bearings 4 and 5 adapted to receive a crank shaft 6 having the usual power driven wheel 7. The machine is provided with the usual treadle 8 with suitable connecting mechanism 90 10—11 for the clutch adapted to connect and disconnect the wheel 7 from the crank shaft. The crank shaft 6 is connected to a rotary cam ring 15 by means of a connecting rod 12 carried respectively by 95 cranks or crank pins 13 and 14. To the base of the machine is bolted or otherwise secured a forming mechanism support or head 16 shown as circular and provided centrally thereof with a forming arbor 21. 100 A bushing 46 is held in an opening in the support 16 by means of three collar screws 55, one being shown in Fig. 4 and the forming arbor 21 is securely held in this bushing by means of a screw 56 and washer as illustrated in this figure.

105 The camming ring 15 is so mounted with respect to the forming head 16 as to have a rotary movement relatively thereto and in order to accomplish this the camming ring 110

is held in position on the forming head 16 by means of three attaching plates 17 securely bolted to the ring (see Fig. 4) and adapted to slide in grooves 17^a formed in the periphery of the forming base 16. Attached to the camming ring 15 by means of bolts 19 are a plurality of cams 18, three being provided by way of illustration in the present instance, and by means of slots 20 the cams may be adjusted in position as desired.

Bolted to the front face of the forming head 16 are slide supporting members 25 and 26 (see Figs. 3 and 5), forming ways or guides for the slides 27. These slides 27 are provided with slots 29 at their outer ends for the reception of rolls 28 mounted on studs 30. The forming jaws 31, the working faces of which have a curved or segmental formation, are secured to the slides 27 by means of a rib 33 inserted in a slot 34 in the slide and bolted thereto. These slides 27 are each adapted to be normally held in idle or open position, as illustrated in Fig. 3, by means of a coiled spring 35. This spring is confined in a hole 36 (see Figs. 4 and 5) drilled at the junction of the slide bearing members 25. The free end of the spring is carried in a sleeve 37, which is connected to the slide 27 by means of a pin 38. This pin may be screwed into the side of the sleeve and fits into a hole in the slide. A portion of the slide bearing members 25 is cut away as at 39 shown in Fig. 4 to form a slot between the two members through which the pin 38 is adapted to operate.

In operation the unformed piece 22 is placed upon the arbor 21, and when the clutch 9 is engaged, the crank shaft makes one revolution thereby causing the cam ring 15 to make about one-eighth of a revolution in a counter-clockwise direction, and then return to idle position. When the cam ring 15 revolves on the forming head 16 the cams 6 are brought into engagement with the rolls 28 carried in slides 27. By this action of the cams, the slides carrying the forming jaws 31 are forced toward the arbor 21 to the closed position shown in Fig. 7 and the piece to be formed is pressed tightly between the arbor and the jaws, thus forming it into the finished piece 23 shaped as illustrated in Fig. 11.

During the last part of the revolution of the crank shaft, which is about one-eighth of a turn and when the cam ring 15 has nearly returned to its position of rest, and after the forming jaws 31 have opened by means of springs 35 sufficiently to allow the removal of the formed piece 23, a cam 40 (see Figs. 2 and 9) engages a knock-out lever 41, thus actuating the same and resulting in the ejection of the finished piece 23 from the arbor 21. This is accomplished by

means of an ejector ring 42 (see Figs. 4 and 8), which has a free sliding fit on the arbor, and which of course must be changed in case it is desired to use a different size arbor. For the purpose of enabling the ring 42 to be changed or replaced, three rods 43 are riveted into the ejector ring as shown in Fig. 8, and these rods are attached to ejector rod 44 with set screws by means of the collar 45. The rods 43 slide freely through holes in bushing 46.

The knock-out or ejector lever 41 has a cushioned or safety connection on the rod 44 by means of two springs 47 held in position by means of fastening collars 48 as illustrated in Fig. 2. This cushioned connection is designed for the purpose of eliminating any accidental damage to the mechanism in case the slides 27, which as hereinbefore stated, are returned to idle or open position by springs 35, should for any reason fail to operate, in which case the ejector ring would strike against the ends of jaws 31. Thus the resilient connection of the knock-out lever 41 to the ejector rod 44 in such a case would operate to prevent damage to the ejector ring 42 in contacting with the jaws 31.

The collar 50, which carries the knock-out cam 40 may be the usual brake collar used on conventional power presses. This knock-out cam 40 is fitted into a groove cut in the side of the collar 50, and is held by screws, and as illustrated in Fig. 9, may be adjusted in the desired position for the proper timing of the ejector.

The forming arbor 21 (see Fig. 4) is preferably shaped so as to have substantially a cylindrical body portion 60, an intermediate portion 61 having a tapered formation, and an outer end portion 62, illustrated in the present instance as "cylindrical" in shape, although of course the end portion 62 may be formed in cross section of any desired shape, i. e., hexagonal or square. Each of the segmental jaws 31 have their under surfaces in like manner formed to correspond and cooperate with the surfaces 60, 61 and 62, as shown particularly at 63, 64 and 65, in Fig. 6. The edges of the jaws 31 are beveled at 66, in the present instance at substantially 120° so that in the closed position of the jaws 31 as seen in Fig. 7 the adjacent beveled edges thereof will coincide and the segmental portions 32 will unite into a completely formed bore having substantially continuous unbroken walls. Although the applicants have illustrated in the present case three slides 27 and jaws 31, it is obvious that a larger or smaller number may, if desired, be employed without departing from the spirit of the invention, and in such cases the bevels 66 would be made at such angle as to cause the adjacent jaws to cooperate with each other as above described.

It will be observed from Fig. 10 that the unformed coiled piece or collet 22 comprises a hollow or tubular body portion having projecting portions or finger pieces 22'. This body portion also may preferably be provided with a shouldered portion 24'. The arbor 21 comprises a body portion 60 of substantially the same diameter as the bore of the shoulder portion 24' of the piece 22, 10 when a shoulder is formed prior to the forming of the fingers thereby to permit the collet to be slipped on and off of the arbor. The projecting portion of the piece 22 may be shaped in any desired manner so as to 15 comprise a gripping portion adapted to grip and feed the work when the collet in use is attached to the feed member of a metal working machine. When, as shown in Fig. 10, the collet is provided with the shoulder 20 portion 24' prior to the shaping of the fingers, the bore of the jaws 31 formed by the segmental faces 63 will have substantially the same diameter as the larger diameter of the body of the collet. In the present case, 25 for the purpose of illustration, we have shown the collet body with three projecting portions or finger pieces 22' although of course it is readily understood that a less number or a larger number may be provided 30 without in any way affecting the present invention, the essence of which is to shape the projecting portion or portions of the coiled collet body into gripping portions. In the present case the arbor has a tapered portion 35 61 and the segmental part 32 of the jaws 31 has a correspondingly tapered portion 64. The shape of these parts may be varied as the occasion demands, and as heretofore stated, the portions 62 and 65 may be hexagonal, cylindrical, square, etc., to provide 40 correspondingly shaped gripping portions 22' to correspond to the shape of the work to be gripped thereby.

Although we have described a preferred embodiment of our invention, it is to be understood that we do not limit or confine ourselves to the exact construction disclosed, but may make such changes in details of construction or otherwise as will not depart 50 from the spirit of our invention, as defined in the appended claims.

We claim as our invention:

1. In a collet forming machine, the combination of collet supporting means adapted 55 to receive a tubular feed collet body having a projecting portion, and forming means adapted to coat therewith for shaping the gripping portion of a collet, each of said means constructed to have a plurality of forming surfaces of different sizes, and means for moving one of said means relatively to the other in a plane transverse to the collet.
  2. In a collet forming machine, the combination of collet supporting means adapted 65
- to receive a tubular feed collet body having a projecting portion and forming means adapted to coat therewith for shaping the gripping portion of a collet, each of said means constructed to have a plurality of 70 contiguous lengthwise extending forming surfaces of different sizes and lying in different planes, and means for moving one of said means relatively to the other in a plane transverse to the collet. 75
3. In a collet forming machine, the combination of collet supporting means adapted to receive a tubular feed collet body having a projecting portion and forming means adapted to coat therewith, each of said 80 means constructed to have a plurality of forming surfaces of different sizes, and including an intermediate tapering portion, and means for moving one of said means relatively to the other in a plane transverse 85 to the collet.
4. In a collet forming machine, the combination of collet supporting means adapted to receive a feed collet body, and forming means adapted to coat therewith, said supporting means and forming means having cooperating forming surfaces of reduced size operative to shape a part of said collet body into a gripping portion, and means for shifting one of said means relatively to the other in a plane transverse to the other. 90
5. In a machine of the class described, the combination of collet supporting means provided with an intermediate tapered portion and adapted to receive a hollow tubular feed 100 collet body having projecting finger pieces, means provided with a corresponding tapered portion and cooperating with said first means for shaping said finger pieces into gripping fingers provided with intermediate tapered portions, and means for moving one of said means relatively to the other to form each finger with an intermediate tapered portion and a terminal gripping portion. 105
6. In a machine of the class described, the combination of collet supporting means and radially movable means adapted to receive a feed collet body therebetween and having each a cylindrical portion and a 110 forming portion of reduced size, and means for shifting said movable means to form a part of said collet body into a gripping portion of reduced size corresponding to said forming portion. 115
7. In a machine of the class described, the combination of means comprising an arbor for supporting a collet forming blank, means for shaping the blank against said arbor, means for shifting said means 120 one relatively to the other, and means for shifting said blank. 125
8. In a collet forming machine the combination of collet supporting means and forming means adapted to receive a feed 130

collet body therebetween and having each a relatively large portion and a forming portion of reduced size, and means for moving said means one relatively to the other to 5 form a part of said collet body into a gripping portion of reduced size corresponding to the reduced size of said forming portion.

9. In a collet forming machine, the combination of collet supporting means and forming means adapted to receive a feed collet body therebetween and having each a tapered portion and a forming portion of reduced size, and means for moving said 10 means one relatively to the other to form 15 a part of said collet body into a tapered portion corresponding to said tapered portion and a part into a gripping portion of reduced size corresponding to the reduced 20 size of said forming portion.

10. In a collet shaping machine the combination of collet supporting means comprising an arbor, forming means adapted to co-act therewith for forming the gripping 25 portion of the collet, means for shifting one of said means toward and from the other, and means for shifting the collet.

11. In a collet shaping machine, the combination of collet supporting means, 30 forming means adapted to cooperate therewith and constructed for forming the gripping portion of the collet, said supporting means having a shape corresponding to the entire interior shape of said gripping portion and means for shifting one of said 35 means toward and from the other.

12. In a collet shaping machine, the combination of collet supporting means comprising an arbor, forming means adapted 40 to cooperate therewith for forming the gripping portion of the collet, means for shifting one of said means toward and from the other, and means for ejecting the collet from said arbor.

45 13. In a collet shaping machine, the combination of collet supporting means, forming means cooperating therewith for shaping the gripping surface of the collet, and means for actuating one of said means toward and from the other, said actuating means comprising an oscillating cam mechanism.

50 14. In a collet shaping machine, the combination of collet supporting means, forming means cooperating therewith for shaping the gripping surface of the collet, and means for actuating one of said means toward and from the other, said actuating means comprising an oscillating cam mechanism and said forming means comprising a plurality of shiftable jaws movable toward and from said supporting means.

55 15. In a collet shaping machine the combination of supporting means and a plurality of cooperating collet shaping jaws

each having a lengthwise extending operating face having different sizes, and means for operating said jaws to form a tubular collet having different diameters, said supporting means constructed to permit movement of the collet thereon.

16. In a collet shaping machine the combination of supporting means and a plurality of cooperating collet shaping jaws each having a lengthwise extending operating face divided into portions of different sizes including a tapered portion, and means for operating said jaws to form a tubular collet having different diameters, said supporting means constructed to permit movement of the collet thereon. 75

17. In a collet forming machine, a forming arbor adapted to receive a feed collet, forming means movable to and from said arbor, rotary means for moving said forming means at predetermined times toward said arbor, and resilient means for moving said forming means away from said arbor. 85

18. In a collet forming machine, a forming arbor adapted to receive a feed collet, a plurality of movable jaws, camming means effective at predetermined times to move said jaws toward said arbor, and means for returning said jaws, said camming means 90 having an oscillatory movement.

19. In a collet forming machine, a forming arbor adapted to receive a feed collet, a plurality of movable segmental jaws, rotary camming means effective at predetermined times to move said jaws toward said arbor, and resilient means for returning said jaws, said camming means having an oscillatory movement, and means for oscillating said camming means. 100

105 20. In a collet forming machine, the combination of a collet supporting forming arbor adapted to receive a feed collet, a plurality of movable finger forming jaws adapted to cooperate with said arbor, a camming ring having means operative to move said jaws toward said arbor, and means comprising a crank shaft for operating said camming ring.

110 21. In a collet forming machine, the combination of a collet supporting forming arbor adapted to receive a feed collet, a plurality of movable finger forming segmental jaws adapted to cooperate with said arbor, an oscillatory revolving camming ring having means operative to move said jaws toward said arbor, and means comprising a crank shaft for revolving and oscillating said cam ring.

115 120 125 22. In a collet forming machine, the combination of a collet supporting forming arbor, adapted to receive a feed collet, a plurality of finger supporting jaws, slides carrying said jaws, camming means rotatable in one direction to move said slides thereby 130

to close the jaws and rotatable in the opposite direction to release said slides.

23. In a collet forming machine, the combination of supporting means, a forming head carried thereby and a detachable collet supporting core secured to the center thereof, a plurality of radially shiftable finger forming jaws carried by said forming head, an oscillatory cam carrying ring carried by said head, means for oscillating said ring thereby to shift the jaws toward the core, and means for shifting said jaws away from the core.

24. In a collet forming machine, the combination of a supporting means, a forming head carried thereby and a detachable core secured to the center thereof, a plurality of radially shiftable jaws carried by said forming head, an oscillatory cam carrying ring carried by said head, means for oscillating said ring thereby to shift the jaws toward the core, and means for shifting said jaws away from the core, said ring operating means including clutch control means.

25. In a collet forming machine, the combination of a supporting means, a forming head carried thereby and a detachable core secured to the center thereof, a plurality of radially shiftable jaws carried by said forming head, an oscillatory cam carrying ring carried by said head, means for oscillating said ring thereby to shift the jaws toward the core, means for shifting said jaws away from the core, said ring operating means including clutch control means, and ejector mechanism including means encircling the core for ejecting the collet.

26. In a collet forming machine, the combination of a collet supporting forming arbor having a plurality of lengthwise extending forming surfaces, a plurality of shiftable segmental jaws, camming means rotatable in one direction thereby to shift said jaws to a closed position and cooperating with said arbor, and rotatable in a reverse direction to release said jaws.

27. In a collet forming machine, a forming arbor having different diameters and adapted to receive a feed collet, a plurality of shiftable segmental jaws, camming means rotatable in one direction thereby to shift said jaws to a closed position and cooperating with said arbor and rotatable in a reverse direction to release said jaws, means for opening said jaws, and means for rotating said camming means.

28. In a collet forming machine, the combination of a collet supporting forming arbor having different lengthwise extending forming faces, a plurality of jaws radially movable relatively to said arbor to and from a closed position and having a plurality of different lengthwise extending forming faces corresponding to the faces of said ar-

bor, camming means rotatable in one direction thereby to move said jaws to a closed position and rotatable in a reverse direction to release said jaws, said jaws in closed position having the forming faces thereof cooperating with the forming faces of said arbor.

29. In a collet forming machine, a forming arbor having different diameters and adapted to receive a feed collet, a plurality of jaws radially movable relatively to said arbor to and from a closed position and having a plurality of segmental faces corresponding to the faces of said arbor, camming means rotatable in one direction thereby to move said jaws to a closed position and rotatable in a reverse direction to release said jaws, said jaws in closed position having the segmental faces thereof cooperating with the faces of said arbor, means for opening said jaws, and means for ejecting the feed collet from said arbor.

30. In a collet forming machine, a forming arbor having different diameters and adapted to receive a feed collet, a plurality of jaws radially movable relatively to said arbor to and from a closed position and having a plurality of segmental faces corresponding to the faces of said arbor, camming means rotatable in one direction thereby to move said jaws to a closed position and rotatable in a reverse direction to release said jaws, said jaws in closed position having the segmental faces thereof cooperating with the faces of said arbor, means for opening said jaws, and means for ejecting the feed collet from said arbor and comprising an ejector ring shiftable over said arbor.

31. In a collet forming machine, a forming arbor having different diameters and adapted to receive a feed collet, a plurality of jaws radially movable relatively to said arbor to and from a closed position and having a plurality of segmental faces corresponding to the faces of said arbor, camming means rotatable in one direction thereby to move said jaws to a closed position and rotatable in a reverse direction to release said jaws, said jaws in closed position having the segmental faces thereof cooperating with the faces of said arbor, means for opening said jaws, and means for ejecting the feed collet from said arbor and comprising an ejector ring shiftable over said arbor, an ejector rod, and a knock-out lever.

32. In a collet forming machine, a forming arbor having different diameters and adapted to receive a feed collet, a plurality of jaws radially movable relatively to said arbor to and from a closed position and having a plurality of segmental faces corresponding to the faces of said arbor, camming means rotatable in one direction thereby to move said jaws to a closed posi-

tion and rotatable in a reverse direction to release said jaws, said jaws in closed position having the segmental faces thereof cooperating with the faces of said arbor, 5 means for opening said jaws, means for ejecting the feed collet from said arbor and comprising an ejector ring shiftable over said arbor, an ejector rod, a knock-out lever, and a cam engaging at predetermined times 10 said knock-out lever.

33. In a collet forming machine, a forming arbor having different diameters and adapted to receive a feed collet, a plurality of jaws radially movable relatively to said arbor to and from a closed position and having a plurality of segmental faces corresponding to the faces of said arbor, camming means rotatable in one direction thereby to move said jaws to a closed position and rotatable in a reverse direction to release said jaws, said jaws in closed position having the segmental faces thereof co-operating with the faces of said arbor, means for opening said jaws, means for ejecting the feed collet from said arbor and comprising an ejector ring shiftable over said arbor, an ejector rod, a knock-out lever, and a cam engaging at predetermined times said knock-out lever, said knock-out lever having a resilient connection with said ejector rod.

34. In a collet forming machine, the combination of collet supporting forming arbor adapted to receive a feed collet, a plurality of shiftable segmental jaws radially shiftable relatively to said arbor to and from a closed position, a rotary camming ring having means movable in one direction to shift said jaws to a closed position and movable in the opposite direction to release said jaws, means comprising a rotary shaft for rotating said camming ring, resilient means for opening said jaws, and means for ejecting the feed collet from said arbor.

45 35. In a collet forming machine, the combination of collet supporting forming arbor adapted to receive a feed collet, a plurality of shiftable segmental jaws radially shiftable relatively to said arbor to and from a closed position, a rotary camming ring having means rotatable in one direction to shift said jaws to a closed position and rotatable in the opposite direction to release said jaws, means comprising a rotary shaft for rotat-
50 ing said camming ring, resilient means for opening said jaws, means for ejecting the feed collet from said arbor and comprising ejector means movable over said arbor, and means controlled by said shaft for actuating
55 at predetermined times said ejector means.

36. In a collet forming machine, a forming arbor adapted to receive a feed collet, a plurality of shiftable segmental jaws radially shiftable relatively to said arbor to and from a closed position, a rotary camming

ring having means rotatable in one direction to shift said jaws to a closed position and rotatable in the opposite direction to release said jaws, means comprising a rotary shaft for rotating said camming ring, resilient means for opening said jaws, means for ejecting the feed collet from said arbor and comprising ejector means movable over said arbor, and means controlled by said shaft for actuating at predetermined times said ejector means and comprising a knock-out lever having a cushioned connection with said ejector means. 70 75

37. In a collet shaping machine, the combination of a pair of means movable one relatively to the other and constructed for forming the gripping portion of a feed collet for metal working machines, one of said means comprising a collet supporting arbor adapted to receive a feed collet and the other comprising one or more forming members, and means for moving one of said means relatively to the other. 80 85

38. In a collet shaping machine, the combination of a pair of means movable one relatively to the other and constructed for forming the gripping portion of a feed collet for metal working machines, one of said means comprising a collet supporting arbor adapted to receive a feed collet and the other comprising one or more forming members, and means for moving one of said means relatively to the other and comprising a movable camming element. 90 95

39. In a collet shaping machine, the combination of a pair of means movable one relatively to the other for forming the gripping portion of a feed collet for metal working machines, one of said means comprising a collet supporting arbor adapted to receive a feed collet and the other comprising one or more forming members, means for moving one of said means relatively to the other and comprising a movable camming element, and means for ejecting the collet from said arbor. 100 105 110

40. In a collet shaping machine, a pair of means movable one relatively to the other for forming the gripping portion of a feed collet for metal working machines, one of said means comprising an arbor adapted to receive a feed collet and the other comprising one or more forming members, means for moving one of said means relatively to the other and comprising a movable camming element, means for ejecting the collet from said arbor, said means comprising an ejector ring, an ejector rod connected thereto, a knock-out lever having a cushioned connection with said ejector rod, and a movable element adapted to engage at predetermined times said knock-out lever. 115 120 125

41. A machine of the class described comprising collet supporting means adapted to receive a hollow feed collet body having pro- 130

jecting finger pieces, finger forming means movable relatively thereto for operating on said finger pieces and forming gripping fingers terminating in gripping portions, 5 and means for ejecting the collet from said first means.

42. A machine of the class described comprising collet supporting means adapted to receive a hollow feed collet body having projecting finger pieces, finger forming means movable relatively thereto for forming therefrom fingers having gripping portions, and means for ejecting the collet from said first means.

15 43. A machine of the class described comprising means adapted to receive a hollow feed collet body having projecting finger pieces, means movable relatively thereto for shaping said finger pieces into gripping 20 fingers adapted to successively grip the

work, and cushioned means for ejecting the collet from said first means, said ejecting means constructed to permit variable sizes thereof to be used corresponding to the size of said first means.

25

44. In a collet shaping machine the combination of means adapted to support a hollow feed collet body having a projecting portion, forming means movable relatively thereto for forming said projecting portion 30 into a gripping portion, means for ejecting the collet from said first means, said ejecting means being constructed to permit variable sizes thereof to be used corresponding to the size of said first means.

35

Signed at Windsor, Vermont, this 6th day of December, 1920.

CHARLES J. FANCHER.
ROBERT A. JOHNSON.
